1

The present invention relates to methods and apparatus for the continuous centrifugal separation of solid particles from a liquid in which they are dispersed, with the possibility of washing these particles by another liquid.

Up to the present time, centrifugal separation of solid particles from a liquid in which they are in suspension could not be obtained in continuous operation. As a rule, the suspension to be treated is subjected to centrifugal action and the clarified liquid is removed until the solid deposit reaches a given thickness on the peripheral wall of the centrifugal apparatus. The separation operation is then stopped and the deposit is removed through any suitable mechanical means. Finally, if the muddy deposit that has been separated is to be washed, it is necessary, with apparatus of the kind, to place it again in suspension and to subject the new suspension thus formed to further centrifugal treatments.

Apparatus of the type used for separating cream from milk, in which the separation and extraction take place in a continuous manner, are perfectly well adapted to the separation of emulsions of two liquids. But they cannot be used for the separation of solid particles in suspension, where the densities of the suspensions are liable to vary during the separation operation, because in this case, the equilibria that are obtained are unstable and simultaneous evacuation of the liquid and the mud formed by the solid particles is no longer possible.

Other types of apparatus have also been proposed but, up to the present time, none of them has given practical results.

The object of the present invention is to provide a method and apparatus for obviating these difficulties and ensuring, with a continuous operation, the separation of solid particles from a liquid in which they are in suspension.

With this object in view, according to a feature of my invention, the suspension of solid particles in a liquid is treated in a centrifugal apparatus and the mud that collects at the periphery of this apparatus is driven in a centripetal direction by a stream of water or any other liquid the pressure of which is automatically regulated in accordance with the very operation of the apparatus.

According to my invention, this regulation of the pressure of the water or other liquid that drives the mud in the centripetal direction is assured in a very simple manner by feeding said liquid from the center toward the periphery

2

through a suitable supply conduit, while the mud carried along by said liquid is evacuated from the periphery toward the center through a suitable evacuation conduit. With a suitable choice of the respective dimensions of the various parts of the apparatus, the level of said liquid in the feed conduit establishes itself automatically at a distance from the axis of rotation such that there is always sufficient pressure for driving along the heavy elements, whatever be its variations resulting from variations of the percentage of heavy elements, of densities, viscosities, and so on. The rate of flow of the liquid stream maintains itself always at the selected value and the flow of the heavy elements is thus ensured, because instability of the equilibrium is automatically corrected.

With this arrangement, the discharge orifices, which may be either calibrated orifices or ordinary orifices, are located far enough from the periphery so that they can have a relatively large cross-section and, hence, not be liable to plugging.

Finally, the relative rate of flow of the auxiliary liquid, that is to say of the liquid for carrying off the heavy particles, may be made such that a portion of this liquid flows (ascends) outside the evacuation conduit into the centrifugal bowl, and in countercurrent fashion with respect to the movement of the heavy elements which flow toward the periphery. The deposit is thus washed in the best possible conditions, if a certain dilution of the evacuated clarified liquid is not objectionable.

The method according to the present invention further permits of replacing, in a suspension, the dispersing liquid by another one.

According to another feature of my invention, the method and apparatus for the continuous centrifugal separation of solid particles from the liquid in which they are dispersed, as above set forth, is applied to the separation of "red muds" in suspension in solutions of sodium aluminate, obtained in the alkaline treatment of bauxite in autoclaves, which separation is to be carried out during the manufacture of alumina according to the Bayer process.

In actual practice, this operation is nearly always carried out by applying continuous decantation by the mere action of gravity after a suitable dilution of the suspension obtained from the autoclave. Methodical washing of the thickened mud collected at the bottom of the decantation apparatus is then carried out, mostly by means of apparatus working on the same

principle. The disadvantage of such a method of operation is that it involves a long time of contact of the metastable sodium aluminate solutions with red mud, which constitutes, according to my experiments, an active agent for starting decomposition. Retrogradations (precipitation), in the course of the gravity decantation method, can be partly avoided but at the expense of maintaining a very high temperature in the decanting and washing apparatus. The safety limits of temperature from this point of view are given in a paper of G. Bauermeister and W. Fulda (Aluminium, No. 3, March 1943, pages 97-100). Thus for a concentration in caustic Na_2O of 130 gr. per litre, the molecular ratio of caustic Na_2O to Al_2O_3 of the sodium aluminate solutions in equilibrium varies, as follows, as a function of the temperature:

Temperature—89° C., 94° C., 100° C.

Ratio of caustic Na_2O to Al_2O_3 —2.16, 2.03, 1.78

Now, in actual practice, the temperature of a decantation apparatus hardly exceeds 95° C. and the molecular ratio of caustic Na_2O to Al_2O_3 of the aluminate liquors that leave the autoclave is generally close to 1.8. It is therefore obvious that the solutions that are treated are metastable and that a more or less advanced decomposition is always to be feared. This fact is well known to the experts on alumina, who are aware that a slowing down of the decantation process is almost sure to cause a drop in the yield of the plant. This effect is particularly serious when the treatment in the autoclave is carried out at temperatures sufficiently high for permitting the treatment of large charges of bauxite, and the obtainment of aluminate liquors having a lower caustic Na_2O to Al_2O_3 ratio, for instance, ranging from 1.5 to 1.6.

Finally, the susceptibility of red mud to decantation varies substantially according to the qualities of bauxite that are treated. This may produce disturbances in the decantation process due to a sudden change in the nature of the ore that is being treated, these disturbances also influencing the yield of the plant.

The application of the decantation method and apparatus according to the present invention to the treatment of red mud enables a great increase in the rate of decantation of said mud, which considerably reduces the time in which the liquid and the red mud are in contact with each other, and also renders negligible, with respect to the new rate of deposition, any possible variations in the decantation aptitude of the various red muds. Finally, the application of this method further has the double advantage of making it possible to perform decantation at a much lower temperature and to make use for the washing operation of a much smaller proportion of water, this double advantage resulting in an important economy of fuel.

The invention can be carried out with centrifugal apparatus of all kinds. The annexed drawings show, by way of example, the application of the invention to the case of centrifugal apparatus comprising a container fitted with a plurality of superposed discs or conical elements, and to that of a centrifugal apparatus provided with a plurality of peripheral cones, but these examples should not be considered as having any limitative character.

Preferred embodiments of the present invention will be hereinafter described with reference

to the accompanying drawings, given merely by way of example, and in which:

Fig. 1 is a vertical sectional view of an apparatus made according to a first embodiment of the invention;

Fig. 1a is a detail view in section on the line I—I of Fig. 1;

Fig. 2 is a view, partly in elevation and partly in vertical section, of a second embodiment;

Fig. 2a is a view, partly in elevation and partly in vertical section, of a slight modification of the embodiment shown in Fig. 2;

Fig. 3 is a plan view corresponding to Fig. 2;

Fig. 4 is a sectional view of a modification of the apparatus of Fig. 1;

Fig. 5 is a sectional view of a modification of the apparatus of Fig. 2;

Fig. 6 is a plan view corresponding to Fig. 5;

Fig. 7 is an axial sectional view of a centrifugation cone;

Fig. 8 is an axial sectional view of the end of a cone of a machine according to a modification of that shown by Fig. 7;

Fig. 8a is a perspective view of the same arrangement as Fig. 8;

Fig. 9 is a view partially in elevation and partially in axial section on the line IX-IX of Fig. 8;

Fig. 10 is a sectional view of the end of a cone of a centrifugal machine, made according to still another modification.

In the embodiment illustrated by Fig. 1, the apparatus includes a main body 1 and a cover 2 fixed to said main body by means of a nut ring 3. A plurality of conical plates 18 are superposed in body 1. The mixture to be decanted or separated is introduced through tube 6 into the space between partition 9 and the bottom of body 1 and it is led to the base of the pile of plates 18 on the outer side thereof.

The heavy elements or particles collect at the periphery of body 1, where they meet with liquid streams of centripetal direction. These heavy elements are driven into and through pipes 4 and evacuated through calibrated orifices 5. The mud that accumulates at the periphery of the container formed by body 1 and cover 2 forms funnel-shaped deposits around pipes 4, the spaces limited by these funnel-shaped mud deposits serving in the separation operation.

The liquid for driving out these heavy elements is introduced through conduit 13 into distributing means where it is divided into as many equal portions as there are devices for the evacuation of the heavy elements.

Each of these portions is led, through pipes 15, disposed between partition 9 and the bottom of body 1, to the points of the periphery where the heavy elements collect together.

The liquid in course of clarification ascends between discs 18 and flows out in the clarified state through calibrated orifice 12.

In the embodiment illustrated by Figs. 2 and 3, the apparatus includes a central body 1' on which are fixed a plurality of cones 2' located either all in the same plane or in different parallel planes.

These cones include a partition 3', also of conical shape, and an axial pipe 4' leading to calibrated orifices 5'.

The mixture to be separated or decanted is introduced through conduit 6' into distributing device 1' where, by means of a set of radial partitions, it is divided into as many equal portions as there are cones 2' in the apparatus.

Each of the cones thus receives, through con-

duit 8', a portion of this mixture, which is fed to a distributor 9' fitted with a perforated partition 10' for equalizing the rate of flow into cone 2' where decantation or separation is to take place.

The clarified liquid flows inwardly between distributor 9' and partition 3', enters space 11' and escapes through calibrated orifices 12'.

The heavy elements collect at the apex of the cone, where they meet with a stream of liquid of centripetal direction. These elements are driven into pipe 4' and evacuated through calibrated orifice 5'.

The driving liquid is fed through conduit 13' into passage 15' between cones 2' and 3', after passing through distributing device 14' where, owing to the action of a plurality of radial partitions, it has been divided into as many equal portions as there are cones.

Each portion of said liquid is thus led to the apex of a cone 2', where it is caused to flow in a centripetal direction, and thus meets the heavy elements.

In both of the embodiments above described with reference to Figs. 1 to 3, I may cause a portion of the liquid of the initial suspension to flow out through conduits 4 or 4'. I may also cause a portion of the auxiliary liquid to mix with the liquid of said suspension. For this purpose, it suffices, for instance, either to reduce or to increase the volume of liquid introduced into distributing device 14 or 14'.

The distance between the various parts of centrifugal apparatus is suitably determined in such manner that the liquid level in conduit 15' is normally located in the middle part of this conduit. In case of variation of the pressure necessary for driving along the heavy elements, this level very quickly comes to such a distance from the axis of revolution that the variation of pressure that results from this variation of position of the liquid level keeps the flow of liquid at the chosen rate.

In the case of devices of the kind shown by Figs. 2 and 3, the same pressure variations take place under the effect of similar causes in the conduit 8' through which the mixture to be separated is introduced and give the same result of keeping the rate of flow of this mixture to a uniform rate.

In addition to the action exerted by the volume of the liquid and that of the mixture introduced into the apparatus, it is further possible, by varying the sections of orifices 5' and 12', to modify the working conditions of said apparatus and, in particular, to act upon the proportion of water mixed with the clarified liquid or of suspension liquid evacuated together with the heavy elements. It is thus possible to vary within wide limits the conditions of washing of said elements.

The apparatus illustrated by Figs. 1, 2 and 3 are given merely by way of example, and many modifications can be made therein without departing from the principle of the invention. For instance, the calibrated orifices 5' and 12' of Fig. 2 can be replaced by tubes 16 and 17 and vent-holes 19^a and 19^b, as shown in Fig. 2a. In this case, the rate of flow is determined by giving suitable lengths to tubes 16 and 17, the latter opposing to the circulation of the elements a counter-pressure which is the higher the nearer their orifices are from the axis of rotation *a*—*b*. The sections of these tubes should be chosen relatively large so that only their length need be taken into account, whatever be the rate of flow and the viscosity of the elements conveyed therethrough.

The driving liquid may itself be constituted of a suspension instead of being constituted of a clear liquid. This auxiliary liquid or suspension may, if advantageous, be introduced under pressure, by replacing, for instance, tube 13' of Fig. 2 by an axial tube 13 as in Fig. 1, but provided with a stuffing box. The auxiliary liquid or suspension for carrying along the heavy elements may be introduced by means of a piston pump the discharge pressure of which will add its action to the automatic action of the centrifugal apparatus, so as to overcome the resistances that are opposed to the evacuation of the heavy elements.

I may also introduce into the tube 4 or 4', in addition to the auxiliary liquid, a gas or vapor intended to reduce the weight of the column of suspension to be evacuated. For the same purpose, I may also replace the auxiliary liquid or suspension that is fed through conduit 13 or 13' by an emulsion of a gas or vapor.

In the device of Fig. 1, pipes 4 and 15 may be replaced by annular channels of small width, which makes it possible to dispense with the formation of funnel-shaped stable mud deposits as above set forth, the whole of the bowl being then utilized for decantation of the mixture.

When the density of the dispersive phase, that of the driving liquid, or the proportion of dry material in the dispersed phase vary in the course of a centrifuging operation, the amount of dispersive phase that is evacuated with the dry matters also varies, which may involve certain drawbacks, in particular that of collecting a smaller amount of the dispersive phase that is employed.

The apparatus shown by Fig. 4, which is of a type analogous to that of Fig. 1, makes it possible to vary during the course of the operation the volume of clarified liquid and, therefore, to collect the desired quantity of this liquid.

In this apparatus, the orifices 12^a for the discharge of the clarified liquid open into a circular channel 20 which rotates together with the body 1 of the apparatus. A pipe 21 which acts as a discharge conduit and which does not turn together with body 1, penetrates more or less into said channel 20 and thus permits the variation, in operation, of the level of the clarified liquid, and therefore the hydrodynamic states of equilibrium in the apparatus, whereby it is possible to modify at will the rate of extraction of the clarified liquid from the apparatus.

The degree of penetration of pipe 21 into channel 20 may be varied either manually or automatically as a function of the flow rates.

I may also arrange the heavy elements outlet orifices 5^a so that they open into a circular channel 22, and remove solid particles mixed with the driving liquid by means of a pipe 23 the position of which is adjustable so as to vary the flow rate.

Channels 20 and 22 may be used either simultaneously or separately, orifices 12^a and 5^a being both either calibrated or uncalibrated.

The centrifuging apparatus shown by Figs. 5 and 6 is of a type analogous to that of Figs. 2 and 3. This apparatus includes a system of discharge pipes 21^b and 23^b, analogous to those above referred to, projecting more or less into channels 20^b and 22^b respectively, and designed to receive the outflowing clarified liquid and the mixture of solid particles and of driving liquid.

According to my invention, the apparatus may be arranged in such manner that a portion of the driving liquid is mixed with the liquid of the suspension and performs a relative washing of the mud.

When washing liquid is introduced into the bottom part of a decantation chamber constituted, for instance, by the inner cone 3' of the apparatus of Fig. 5, this liquid produces, if its density be lower than that of the suspension that is being decanted, eddies that are detrimental of the good clarification of the liquid. These eddies are the more pronounced the greater the difference of density and the greater the centrifugal field.

In order to prevent the formation of these eddies, I provide (Fig. 7) in cone 2' a bell or funnel 37 adapted to catch the centripetal streams of diluted suspension and to lead them, through tube 38, into the feed chamber 8' of the apparatus. With this arrangement, the portion of the decantation chamber that is located between the edge of this bell or funnel 37 and the level of evacuation of the clarified liquid is not disturbed by eddies and the clarification of the liquid takes place normally.

According to another feature of my invention, it has been found that it is possible to obtain the separation of the clarified liquid without mixing with the driving liquid.

This result can be obtained by providing at the apexes of the cones of the centrifuging apparatus special devices such as those illustrated by Figs. 8 and 9.

Fig. 8 is an axial cross-sectional view of the apparatus across the cones which it comprises. Fig. 9 is a view partially in elevation and partially in axial section of the same arrangement but through a plane perpendicular to that of Fig. 8 i. e. along line IX-IX of Fig. 8 passing through the central tube through which the muds arrive.

Fig. 8a is a perspective view of the same arrangement in partial cross-section through two axial planes perpendicular to one another, one being that of Fig. 8 and the other that of Fig. 9.

According to the arrangement illustrated by these views, I provide at the interior of the apexes of the cone 2^c of the centrifuging apparatus a removable block 28 upon which concentric tubes 4^c and 29 are fitted. The driving liquid is fed into the annular space between these two tubes and enters conduit 30 provided in block 28. The decanted solid particles, accumulated at the apex of cone 2^c, pass through aperture 31 into conduit 32. One of the ends of the conduit 30 is screwed into the wall of the cone 2^c and the end of this screw forms a tight joint with the block 28. The other end of the conduit 30 is connected to a circular partition, not shown, analogous to the partitions designed for the introduction of the mixture to be decanted and for the driving liquid. In the case of a centrifugation with washing there are therefore three circular coaxial partitions. A conical piece 33, made in the shape of the plug of a cock, is fitted in a fluid-tight manner in a corresponding housing formed in block 28. It serves to connect together the various conduits as shown by the drawing whereby the driving liquid fed through conduit 30 enters conduit 34, which is connected to outlet tube 4^c. Conical piece 33 is provided with a small plate 33a which can be made of any desired length and thickness to obtain a given rate of flow. It is possible, by modifying the length and thickness of this plate 33a, to adjust the rate of flow of the solid particles and of the driving liquid by more or less reducing the cross section of flow through conduits 30 and 32.

If it is desired to wash the heavy elements in the centrifuging machine by means of a liquid other than the driving liquid, use can be made of a device such as shown by Figs. 8 and 9. Ac-

cording to this device, block 28 is provided with a conduit 35 connected with a suitable pipe 36 and opening into conduit 32. The washing liquid can be introduced through conduit 35 into conduit 32 and, therefore, into the decanted heavy elements. The quantity and quality of the washing liquid thus introduced from the outside can be varied during operation of the centrifuging machine. Pipe 36 and conduit 35 may also be used for the introduction of a gas, a vapor or an emulsion.

In the device of Fig. 10, the conical inner partition 34 is provided, at the apex thereof with a block 24 provided with a passage 27 for the evacuation of the decanted solid particles. The driving liquid fed through the space between cones 2^d and 3^d enters block 24 in the centripetal direction in the form of an annular sheet given thereto by a piece 28, of predetermined length and diameter, presenting a double portion substantially conical fixed to the summit of the centrifugal cone. The solid particles that are driven along pass between block 24 and wall 3^d and are conveyed to outlet tube 4^d through conduit 21.

In the particular application of the invention to the decantation of red mud, any of the above described devices can be used. I may, for instance, employ a centrifuging apparatus of the kind illustrated by Fig. 2a including means for annular distribution of the driving liquid such as shown by Fig. 10.

This centrifuging apparatus may, for instance, have the following characteristics:

Speed of revolution—from 1200 to 1500 revolutions per minute;
Distance from the apex of the cones to the axis of revolution—620 mms.;
Height of the cones—200 mms.;
Diameter of the cone bases—240 mms.;
Diameter of the tubes 4 through which mud is evacuated—from 8 to 10 mms.;
Distance a from the mud outlet end of tube 17 to the axis of rotation—260 mms. approximately;
Distance b from the clarified solution outlet end of tube 18 to the axis of rotation—340 mms. approximately;
Diameter of the outlet channels 17 and 18 for the decanted mud and the clarified liquid—from 8 to 10 mms.;
Width c of the annular slot provided for the passage of the driving liquid—0.6 mms.;
Width d of the annular slot provided for the passage of the mud—1 mm.;
Outer diameter of piece 28—22 mms.

The following examples describe, by way of nonlimitative indications, applications of this apparatus to the treatment of red mud in a solution of sodium aluminate by the Bayer process.

Example 1

After withdrawal from the autoclave and dilution, I introduce into the centrifuging apparatus:

a. 5 cubic meters of a suspension containing 175 kgs. of red mud of a density of 3.5 and 4.93 cubic meters of a solution of sodium aluminate of a density of 1.21 (25° Baumé) made up of two molecules of caustic Na₂O per molecule of Al₂O₃.

b. 4.5 cubic meters of an aluminate solution of density 1.1 (13° Baumé) obtained from the

washing of muds and in which the molecular ratio of Na_2O to Al_2O_3 is the same.

I obtain, after treatment in the centrifuging apparatus:

1. 4.5 cubic meters of a clarified solution of sodium aluminate of a density of 1.21 (25° Baumé);

2. 5 cubic meters of a suspension containing 175 kgs. of red mud and 4.95 cubic meters of a solution of aluminate solution of a density of 1.11 (14.28° Baumé);

As the clarified aluminate solution contains 125 grs. per litre of Na_2O , I obtain a clear solution containing 514 kgs. of alumina for the 5 cubic meters of suspension that have been treated.

As the solution of sodium aluminate that is utilized for attacking the bauxite contains four molecules of caustic Na_2O for each molecule of Al_2O_3 , I dissolve, in the treatment of bauxite, 411 kgs. of alumina per ton of caustic Na_2O used.

Example 2

I introduce into the centrifugal apparatus:

a. 5 cubic meters of a suspension containing 325 kgs. of red mud and 4.907 cubic meters of a solution of sodium aluminate of a density of 1.21 (25° Baumé), containing 1.4 molecules of caustic Na_2O per molecule of Al_2O_3 .

I obtain, after treatment in the centrifuging machine:

1. 4.07 cubic meters of a clarified solution of sodium aluminate of a density equal to 1.21 (25° Baumé);

2. 6.43 cubic meters of a suspension containing 325 kgs. of red mud and 6.337 cubic meters of a solution of aluminate of a density of 1.115 (14.85° Baumé).

As the clarified solution of aluminate contains 125 grs. of Na_2O per litre, I obtain a clear solution containing 598 kgs. of alumina and I dissolve, in the course of the treatment of the bauxite, 764 kgs. of alumina per ton of caustic Na_2O used.

Example 3

I introduce into the centrifuging apparatus: *a* and *b*. The same volumes of suspension and of driving liquid as above indicated in Examples 1 and 2; and

c. 0.150 cubic meter of a liquid resulting from the washing of the mud, of a density of 1.1 (13° Baumé), with a view to washing the mud portions separated by centrifuging before their mixing with the driving liquid.

I obtain:

1. 4.22 cubic meters of a clarified solution of sodium aluminate of a density of 1.205 (24.5° Baumé);

2. 6.23 cubic meters of a suspension containing 325 kgs. of red mud and 6.337 cubic meters of a solution of aluminate of a density of 1.105 (13.68° Baumé).

From the clarified solution of aluminate containing 122.5 grs. of Na_2O per litre, I obtain a clear solution containing 604 kgs. of alumina for 5 cubic meters of suspension treated, and I dissolve, in the course of the treatment of the bauxite, 764 kgs. of alumina per ton of caustic Na_2O , as in Example 2.

Various modifications may be brought to the method of treatment set forth in the preceding examples. For instance, the suspension, on leaving the autoclave, may be introduced into the centrifuging machine either as it is or after suitable dilution. The clear liquid that is uti-

lized for the extraction of red mud may be replaced by water, or a suspension of red mud or of any other suitable powdery product. The driving liquid or suspension may also be emulsified inside the apparatus by means of a gas or vapor introduced in any suitable manner. After passage through a thickening device, the suspension of red mud that leaves the centrifuging apparatus may be introduced into a second centrifuging apparatus where separation and washing of the mud will take place. These operations may be pursued in a third centrifuging apparatus and so on. The suspension resulting from the attack of bauxite in the autoclave may, after suitable dilution, be treated in a classifying and selecting apparatus of any suitable type with a view to separating the mud grains of a diameter higher than a given limit (for instance 50 microns). These grains may be treated separately, only the fine portion being introduced into the centrifuging apparatus.

The mud driving liquid may be constituted of the liquor serving to attack the bauxite, in a more or less concentrated state, thus forming a suspension with the mud. This suspension, heated for a further attack, dissolved a further portion of alumina, which had remained in the bauxite after the first attack. This method of operation permits of methodically exhausting bauxite in several operations.

In a general manner, while I have, in the above description, disclosed what I deem to be practical and efficient embodiments of apparatus made according to the present invention, it should be well understood that I do not wish to be limited thereto as there might be changes made in the arrangement, disposition and form of the parts without departing from the principle of the present invention as comprehended within the scope of the accompanying claims.

What I claim is:

1. A continuous method for the centrifugal separation of solid particles suspended in a liquid comprising the steps of, introducing a suspension of solid particles in a liquid into a centrifuge, rotating the centrifuge and effecting the separation of the solid particles from the liquid in the suspension by centrifugal force, removing from the centrifuge the liquid so separated, collecting the separated solid particles at points on the inner periphery of the centrifuge, separately introducing in a centrifugal direction a current of auxiliary fluid into the rotating centrifuge whilst preventing its admixture with the suspension being centrifuged, injecting said current of auxiliary fluid into the collected mass of separated solid particles at the periphery by the effect of the kinetic energy acquired by the moving fluid as it travels towards the periphery, the direction of injection being radial with respect to the axis of rotation of the centrifuge, entraining the separated solid particles in the current of fluid so injected, and discharging by centripetal action the mixture of auxiliary fluid and solid particles entrained therein from the centrifuge.
2. A method according to claim 1 wherein a gas is injected into the mixture of auxiliary fluid and entrained solid particles to facilitate the discharge of the mixture from the centrifuge.
3. A method according to claim 1 in which positive pressure is applied to the auxiliary fluid as it is introduced into the centrifuge.
4. A method according to claim 1 characterized in that the suspension comprises "red mud"

11

in a solution of sodium aluminate as formed in the autoclave in the treatment of bauxite by the Bayer process.

5. A method according to claim 4 characterized in that the original suspension as obtained in the autoclave is diluted and the auxiliary fluid is constituted of a weak solution of sodium aluminate.

6. A process according to claim 4 characterized in that the auxiliary fluid is constituted of a liquor capable of attacking bauxite and further, in that the mixture of such liquor and entrained solid particles discharged from the centrifuge is recycled thereto to effect treatment of further quantities of bauxite.

7. In a continuous centrifugal apparatus for separation of solid particles from a liquid in which they are suspended, a plurality of radially-axised particle collecting cones each cone including means for introducing the solid particle containing liquid, means for introducing in a centrifugal direction an auxiliary fluid, inlet delivery tubes for said auxiliary fluid terminating at a point adjacent the apex and peripheral walls of the cones, discharge tubes extending from a point adjacent the apex of said cone in a radial centripetal direction along the axis and through the entirety of said cone for said solid particle containing auxiliary fluid, a removable block fitted in fluid-tight relationship in the apex of said cones, three parallel ducts located within the block in planes parallel to the axis of said cone, means including a groove interconnecting the ends of the three ducts within the block at a point remote from the other ends of said ducts, the first of the three ducts connected to the inlet delivery tube for the auxiliary fluid, the second of the three ducts openly connected to the interior of the cone at a point adjacent the apex of the cone, and the third of the three ducts connected to the discharge tube for the solid particle containing auxiliary fluid.

8. An apparatus according to claim 7 wherein the means interconnecting the ends of the three ducts within the block is constituted of a removable member and is provided with adjusting means for controlling the discharge for the solid particles containing auxiliary fluid.

9. In an apparatus according to claim 7, a passage extending through the wall of said block and opening into the duct connected to the interior of the cone.

12

10. In a continuous centrifugal apparatus for separation of solid particles from a liquid suspension thereof comprising, a rotating body member provided adjacent its outer periphery with solid particle collecting means of substantially progressively decreasing cross section, means for introducing the suspension into the body member, separate means for introducing in a centrifugal direction an auxiliary fluid into the body member, said last means terminating in an outlet adjacent the smallest cross section of the collecting means whereby the auxiliary fluid is substantially directly injected into the collected mass of separated solid particles, a discharge tube for said particle containing auxiliary fluid extending from a point adjacent said outlet in a radial centripetal direction and through the collecting means, said discharge being connected to an outlet on the exterior of the rotating body member, and independent means for removing the liquid separated from the suspension.

11. An apparatus according to claim 10 wherein the particle collecting means comprise a plurality of radially-axised cones, and each cone is provided adjacent its apex with an inlet for the auxiliary fluid and with a discharge tube for the solid particles containing auxiliary fluid, said tube extending along the axis of the cone.

12. An apparatus according to claim 10 wherein the discharge tube for the particle containing auxiliary fluid is provided with an outwardly flaring funnel-shaped inlet end.

13. An apparatus according to claim 10 provided with deflector means adjacent the outlet for the auxiliary fluid in the collecting means, whereby the auxiliary fluid is injected in an annular sheet into the collected mass of separated solid particles.

JEAN HENRI BOIVINET.
